AUTOMATIC SWITCH

Wilhelm Leyhausen, Nurnberg, Germany

Application June 29, 1951, Serial No. 234,211

20 Claims. (Cl. 200—88)

1

The present invention relates to an automatic switch.

Automatic switches due to their characteristics and advantages are presently being employed on a heavily increasing scale in distribution boards and meter boards as substitutions for fuses.

The present developmental trend in construction of such switches is towards a reduction of space and size factors in order to reduce the size of switches down to that comparable with normal safety fuses. If space and size factors can be reduced to a minimum the advantage is obtained that the dimensions of the distribution board may be reduced and constant or fixed dimensions thereof can be established so that with the minimum size of safety switches maximum circuits may be embodied with distribution or meter boards of these fixed dimensions.

It is necessary however to bear in mind that the reduction in size of automatic switches must be kept within certain limits since the electric switching-off effect must not be reduced by unduly reducing the size of the switch and by reference to the size of switches is meant not only the size of the moving parts but also the casing or base size and therefore in order to comply with these limitations the present invention has for one object to provide automatic switches in which the unused space of the total switch structure is reduced to a minimum. It is a further object to provide an automatic switch which includes a thermic cut-out for overload and an automatic cut-out for sudden overload or short circuit and in connection with such switches it has been found that it is possible to attain a complete utilization of space with consequent reduction in size if the mechanical switch mechanism is separated from the switch components subjected to electrical stress. More particularly the switch contacts the magnetic coil and the means for thermic release, for example a bimetallic strip.

It is therefore an additional object to provide a switch structure of the aforementioned type in which the mechanical switch mechanism and the components subjected to electrical stress are arranged in separate housings. It is a specific object to provide such an arrangement in which the housing parts are arranged in superimposition.

It is a further object to provide such a switch structure of generally rectangular cross section.

An additional object is to provide a specific housing structure for the switch components including U-shaped frames arranged in opposite relation with the bights or connecting portions

2

in juxtaposition thereby providing for ease of assembly.

Consistent with maximum utilization of space in construction of automatic switches of the type referred to, it is an object of this invention to provide improvements in the structural details of such switches including the details of the housing construction and it is also an object to provide a switch structure in which the coil of the magnetic cut-out is mounted beneath a three part knee joint linkage embodied with the mechanical switch components and to structurally dispose the armature of the magnetic cut-out to cooperate with this linkage to provide for sudden disengagement of the switch contacts.

It is an additional object to provide a switch structure in which the housing components for those parts of the switch subjected to electrical stress is divided lengthwise into three spaces or chambers, one constituting the contact chamber, the second receiving the magnetic coil and the third the disengaging elements, that is the armature and the bimetallic member.

It is believed obvious that all types of automatic switches can not be constructed with the same space requirements. In other words, all switches can not be reduced to the same small size such as switches for high current loads, those of the type which embody two magnetic coils, automatic switches with a zero cut-out and those which also embody signal contacts. The dimensions of these latter switches can not be reduced to a degree such that their size will correspond with the size of automatic switches utilized with normal low current values. The latter type switch can have its exterior dimension reduced to a substantially fixed ratio but the more complex switches generally can not conform to the same space requirements. However, the present invention by standardization of the housing components as regards type and manner of assembly provides for ease of production of automatic switches of all types in that the same height factors are present in simple and complex switches with the more simple switches for normal low current values having housing dimensions at the most only half the width of housing dimensions for switches having higher current values. Thus, it is the object of this invention to standardize automatic switch structure in which the space factors of a distribution or meter board are utilized at a maximum degree in that two normal low current value switches occupy the same space as one complex switch therefore providing for easy substitution and

50
55

rearrangement of switches on distribution and meter boards which thus can be standardized as to size and contact arrangements.

Further and more specific objects will be apparent from the accompanying drawings which illustrate two preferred forms of the invention of which Figures 1 to 25 illustrate one embodiment and Figures 26 and 27 illustrate a second embodiment both embodiments being considered as types of switches for normal current values with narrow housings.

In the drawings:

Figure 1 illustrates the first embodiment in vertical section;

Figure 2 is a section on line II--II of Figure 1;

Figure 3 is a section on line III--III of Figure 1;

Figure 4 is a view of a partial detail of Figure 2;

Figure 5 is a view taken along lines V--V of Figure 1, that is with the top of the casing removed;

Figure 6 is a view along lines VI--VI of Figure 2 with the outer switch casing removed;

Figure 7 is a section along lines VII--VII of Figure 6;

Figure 8 is a bottom plan view of the base of the automatic switch of this embodiment;

Figure 9 is a rear elevation of the embodiment with the rear lower U-shaped leg and the closing wall of the contact chamber removed;

Figure 10 is a top plan view of the switch base taken along line X--X of Figure 9;

Figures 11, 12 and 13 illustrate the switch lever in side, top and end elevation, respectively;

Figures 14, 15 and 16 illustrate the hammer lever of the thermic release in side, top and end elevation, respectively;

Figures 17, 18 and 19 illustrate the locking pawl for the thermic release in side, end and top elevation respectively;

Figures 20 and 21 illustrate the magnetic armature and its release lever in plan and end elevation respectively;

Figure 22 illustrates the knee joint linkage including the switch handle;

Figure 23 is a top plan view of a portion of Figure 22; and

Figure 24 is a section taken along line XXIV--XXIV of Figure 22;

Figure 25 is a view corresponding to Figure 6 showing the switch in closing position;

Figures 26 and 27 illustrate a further embodiment of the invention with Figure 27 denoting a view taken along lines XXVII--XXVII of Figure 26;

Figure 28 is a view of a modified form of magnet coil structure utilized with the first embodiment; and

Figure 29 illustrates an arrangement of automatic switches of different widths on a distribution or meter board.

With respect to the first embodiment of the invention as illustrated in Figures 1 to 25 the switch includes a U-shaped frame 2 mounted on a base 1 and which frame houses the switch components subjected to electric stress. The switch chamber 3 embodies therein two fixed contacts 4 and 5 shown more clearly in Figure 9, a movable contact bridge 6, a magnetic coil 7 and its associated armature 8 and a bimetallic element 9 providing for thermic disengagement of the contacts when the current exceeds a predetermined value. The U-shaped frame 2 as shown in Figures 2 and 3 includes a front leg 10, a rear leg 11 and an upper bight or face por-

tion 12 on which rests the face portion 13 of a reversely disposed U-shaped frame including a front leg 14 and a rear leg 15. All of the parts confined within the respective U-frames are covered by a housing 16. The parts or components mounted in these U-frames occupy substantially the same bottom or cross sectional area as the base member which includes a marginal flange or shoulder 17 upon which the housing 16 is mounted. The base is substantially hollow, opening downwardly and provided on its underside with a current conducting strip or rod 18 to which is fastened by means of a screw 109, Figure 1, a contact strip 19 which extends through a lateral recess provided in the base. The contact strip 19 carries a contact terminal 21 having a threaded bore 22 so that a contact screw may be attached thereto for connection to an electrical conductor. The current conducting strip 18 is connected to the fixed contact 4 as shown in Figures 9 and 10. When the switch is closed the current thereby passes through contact 4, the contact bridge 6 to the fixed contact 5 which is connected to the current conducting strip 24 located on the upper face of the base. This strip as shown in Figure 2 terminates in an upwardly extending leg 25 which is connected to a contact piece 108 in turn connected with the innermost winding of the magnetic coil 7. If desired this contact piece 108 may be integral with this innermost winding or integral with the leg 25. On the opposite half of the base, that is on the left half as viewed in Figure 8, there is a current conducting strip 26 having a threaded bore 27 therein on which may be mounted a contact strip 19' by means of screw 109'. This strip 19' carries a contact terminal 21' in a manner similar to the aforescribed arrangement. This contact strip 19' is the conductor to the negative pole and the strip 26 includes an extension 28 projecting upwardly into a recess 29. This extension is provided with a threaded bore 30 as shown in Figures 8 and 10, for cooperation with a screw 31 mounting the bimetallic member 9 as shown in Figure 1. This bimetallic member is connected with the bent end 32 of the outermost winding of the magnetic coil 7. The current therefore flows from contact terminal 21 through the strip 18 and a conductor 23 through contacts 4, 6, 5 thence through the leg 25, strip 24 to the coil 7 and through the offset end 32 of the coil 7, the bimetallic element 9 of the strip 26 thence through the electrical network involved. The switch base is also provided with openings 33 through which threaded screws may pass for fastening the base to the wall or rod. Therefore, as indicated, as long as the contact bridge 6 engages the respective fixed contacts 4 and 5 current will flow through the switch mechanism.

As indicated in Figures 2, 3 and 9 the electrical contacts 5, 6, 4 are disposed in the contact chamber generally denoted at 9. This chamber includes a box like part 34 the rear wall of which is open as shown in Figure 9 and the front wall of which is provided with extensions 35. On the narrow sides of the contact chamber are provided air holes 37 and cooling ribs 38 extend into the interior of the chamber. This box like part or subhousing 34 is closed at its rear by a smooth rear wall 39 as shown in Figures 2 and 3 which wall abuts the leg 11 of the lower U frame 2 and is held thereby. The contact bridge 6 is secured to a contact rod consisting of two cheeks 40 and 41, Figures 2 and 7, and which cheeks hold a

strip 42 therebetween which carries by means of a compression spring acting longitudinally of the strip the contact bridge 6. The strip or rod 42 is connected to the cheeks by rivets not shown. Since these rivets are conductive they are covered by insulating the plates 43 shown in Figure 7. The insulating plates and the contact cheeks 40 and 41 are provided with aligned apertures through which passes a pin 44 connecting them to the switch lever 45 and the connected plates and cheeks are otherwise guided by the marginal edges 46 of an opening 47 in the upper wall of the box like part constituting the contact chamber 3. This is shown in more detail with respect to the modification shown in Figure 28. On the rear wall of the contact chamber 34 lies the magnetic coil 7. This coil has a core 68, Figure 2, arranged in a frame carrying the coil and which frame consists of a cylindrical section 49 and a substantially flat end section 50 shown in elevation in Figure 6 which includes on its front face switch strips 51 and 52. The part 53 terminates at its lower end in a projecting part 53 through which extends contact piece 103 connected with the leg 25 of the current strip 26. The strips 51 and 52 constitute projecting ledges or guides and serve to fix the coil frame and abut on both sides the arms 54 of the front leg 10 of U frame 2 as shown in Figure 1. These arms 54 are provided at their lower extremity with legs or bends constituting lugs 55 which are fastened by means of screws 56 to the base 1. For fastening the rear leg 11 of the U frame 2 to the base this leg 11 is provided on its lower end with a hook like extension 57, Figures 2 and 4, which is inserted from above into a slot 58 in the base and upon subsequent lateral displacement abuts with the face 57a contacting the lower side of the base 1. In assembling the switch, the frame 2 is laterally displaced to engage the hook beneath the base before the arms 54 of the front leg 10 are secured by the screws 56. The two arms 54 are also provided with outwardly projecting lugs 59, Figure 1, through which an axle 60 is passed. The magnet armature 3 is also provided with corresponding lugs 61 and is swingably mounted on the axle 60 under the influence of a spring not shown. The arms 54 of the front leg 10 also define a recess 62 into which the armature 3 may tilt. To limit the motion of the armature toward the coil the same is provided on its sides with lugs 63 which abut against the adjacent arms 54 of the U frame when the armature is attracted by the magnet against the force of the spring.

Within the upper U frame 13, 14 and 15 the mechanical switch mechanism is arranged. Through a recess 64 provided in the front leg 14 a swing lever 65 integral with the magnet armature 3 extends. This swing lever imparts a blow against the under side of a tensioned knee joint linkage comprising three links and shown in more detail in Figures 22 and 24. The linkage includes a first link 66 which is U-shaped in section and rigidly attached by means of an axle 67 to a handle 68, the lever arm 69 of which projects through a slot 70 on the upper side of the casing 16. This link 66 is mounted in a correspondingly shaped recess 71 in the handle 68 so that at most the link can turn relative to the handle to only a limited extent. Between the legs of 70 this link 66 is mounted a bar 72 adapted to contact with and influence a swing lever 73 which is provided on its lower end with a bore 74 by means of which it is fulcrumed on a pin 74a carried by the arm 54 of front leg 10, Figure 1. This

swing lever 73 as shown in Figure 7 extends through a slot 75 in the abutting faces 12 and 13 of the two U frames. A pin 76 pivots swing lever 73 to the second link 77 of the knee joint linkage which latter link in turn is pivoted by pin 78 on the third link 79 of the linkage. As shown the second link 77 which is of U-shaped section is provided on its upper side with a lug 80 abutting the third link 79 as soon as motion of the linkage has passed slightly beyond dead center between the second and third links, 77 and 79. Additionally, the second link 77 has on its lower edge a laterally extending lug 81 projecting into the interior of the housing so that the hammer lever 65 integral with the magnet armature can abut against the same from beneath. As the lever arm 69 is swung to the right the linkage is displaced to the left, compare Figures 6 and 25, to such an extent that the knee joint formed by link 77, swing lever 73 and the U link 66 passes slightly beyond its dead center. In this position, Figure 25, in which also a knee joint 77, 79 has moved slightly beyond its dead center 25 the knee chain therefore is in a substantially rigid condition. Through a bore 82 in the third link 79 passes a pin 83 which pivotally connects the third link 79 with the front leg 84 of the switch lever 45. As shown in Figures 11 to 13 this lever 30 45 is of U-shaped section and by means of bores 85 is swingable about pin 85a fastened in the legs 14 and 15 of the upper U-frame. The rear or longer leg 86 of switch lever 45 has a bore 87 through which passes a pin 44 which holds the contact cheeks 41 constituting the contact carrying bar. The leg 86 of the switch lever 45 is also provided with an angularly offset portion 88 the edge of which abuts against leg 15 of the upper U frame to limit the counterclockwise movement 40 of switch lever 45, see Figure 6. On the upper face of the switch levers are provided two bores 89 and 90 serving to fasten pawl springs 81 and 92. Pawl spring 91 is very strong and engages at its lower end with the axle 100 rigidly mounted between the legs 14 and 15 of the upper U frame and ends to turn switch lever 45 counterclockwise; that is, it urges the same from the position shown in Figure 25 to that shown in Figure 6. Spring 92 engages at its lower end an angular flange 94 of the hammer lever 95 for the thermic cut-out. This hammer lever, as shown in detail in Figures 14 to 16, is pivoted by means of a pin 96 to the front leg 14 of the upper U frame and includes an upstanding lug portion 97 disposed in the recess 64 of the front leg and engaging behind this leg so that it is guided thereby. At the lower end of the hammer lever 95 is a laterally projecting boss or lug 98 adapted to influence the annular part 81 of the second link 60 77 of the knee joint linkage. Spring 91 tends to pull hammer lever 95 upwardly about pin 96 as soon as locking pawl 99, shown in detail in Figures 17 and 19, is disengaged. This pawl 99 pivots on axle 100 and includes a nose portion 101 engaging over the angular portion 94 of hammer lever 95. This nose releases the hammer lever for upward movement as soon as the pawl 99 is turned counterclockwise. This counterclockwise movement is imparted thereto by the bimetallic element 9 which through an adjustable screw 102 presses against the lower end of the pawl 99. For insulation purposes an insulating plate 104 is provided along the lower end of the pawl 99. The switch is placed in operating position, Figure 25, by swinging lever 69 from left to right,

compare Figures 1 and 6, whereby spring 91 is tensioned. If current rises above a predetermined value so that the bimetallic element 9 bends, due to being heated, the pawl 99 is disengaged and hammer lever 95 is released which urged by the spring 92 strikes from beneath against lug 81 of the link 77 of the knee joint linkage. The linkage jumps up thereby permitting switch lever 45 to follow the influence of spring 91 and move counterclockwise so that contact bridge 6 is suddenly elevated and breaks a circuit over contacts 4 and 5. After the upward movement of lug 81 the direction of pressure which the second link 77 of the knee joint linkage exerts on swing lever 73 is different from that exerted in the dead center position so that swing lever 73 can now rotate U-shaped lever 66 and handle 68 about pin 67 and the switching mechanism is moved to the position shown in Figures 1 and 6. This mechanism therefore provides through the action of the bimetallic element a thermic cut-out in the event of overload.

If a short circuit occurs which is a sudden overload so that the magnetic force of coil 7 is abruptly increased, the armature 8 is attracted thereby swinging hammer lever 65 so that the latter hits beneath the angular portion or lug 81 of the knee joint linkage to perform an effect similar to that described with reference to the thermic cut-out. The latter movement, that is the blow of the hammer lever is more enhanced by the fact that its extreme end also strikes directly against the lower edge 101 of arm 84 of switch lever 45 which as shown in Figure 11 is angled so that the hammer lever imparts direct counterclockwise movement to the switch lever.

With reference to Figure 28, there is illustrated a vertical section through a modified form of contact chamber denoted as 3a. The rear wall of the latter is integral with the cylindrical part 49a constituting a coil sleeve while the flat part 50a is a separate piece. The magnet coil 7 may be either wound directly on the cylindrical part 49a or may constitute a packaged coil so that it may be slipped on. The coil sleeve 49a or the coil sleeve 49 of Figure 2 does not necessarily have to have a cylindrical form and can be square or polygonal.

With respect to the second embodiment illustrated in Figures 26 and 27 there is shown an automatic switch in which the mechanical switch mechanism is again spatially separated from the parts subjected to electrical stress and arranged in a housing part lying above the housing receiving the electrical components. The upper and lower housing parts have equal rectangular cross sectional areas. In this modification there is further illustrated a triple division of the lower housing providing an especially efficacious space saving construction. Additionally the base structure is of particular advantage. In Figure 26 the housing consists of a lower part 111, a partition 112 and an upper part 113. The one piece lower part has in its first third area a contact chamber 114 which is separated by a wall 115 from the remaining space of the lower housing part 111. To partly separate both spaces a flange 116 of partition 112 projects beneath the upper terminal edge of partition 115 to provide a labyrinth seal. In contact chamber 114 are mounted the two stationary contacts 117 and the movable contact bridge 118 which is connected to the switch mechanism denoted generally at 133. A T-shaped post 119 projects into contact chamber 114 and includes a front cross plate 119a which guides

the movable contact bridge 118. The web of this T-shaped post prevents the joining of arcs emanating from contacts 117. Behind the front cross plate 119a lie two ferromagnetic sheets 120 which on the one hand constitute the counterpole for the magnet coil 121 and on the other hand serve as a cooling means for the arcs. In order to provide in the switch 133, space for the necessary knee joint linkage, not shown, the movable contact bridge 118 and thereby the two fixed contacts 117 are arranged eccentrically of a lengthwise centerline of a switch as shown in Figure 27. The metal thread of the housing part 111 is occupied by the magnet coil 121 and also houses the coil 122. Upper and lower flanges or ledges 123 and 124 form respectively on the base of the housing 111 and the partition 112 hold the magnet spool so that additional fastening means are not necessary. The last thread of the area of housing part 111 constitutes chamber 125. The magnet armature 127 is movable in this chamber and as shown projects through a slot 126 formed in partition 112. The magnet armature cooperates with the core 122 and acts in a manner similar to the action of the armature 8 in the first embodiment on the release mechanism of switch 122. A push button 128 is attached to the armature 127 to provide for manual current breaking operation of the automatic switch if desired.

On the lower side of the chamber 125 a contact strip 129 is inserted for connection to the electrical circuit and which strip carries the bimetallic member 130. Between the armature 127 and the bimetallic member 130 is a lever constituting a part of the thermic release device. As the bimetallic element bends under the influence of heat the lever 131 is moved by the adjusting screw 132 and thereby effects release of the switch mechanism.

The lower housing part 111 is fastened to the base 135 which latter has on its narrow sides projections 136 each of which is provided with an aperture 137 through which can pass screws or other means for securing the base to a switch board or the like. Likewise the projections also mount the ends 138 of contact strips 129. Contact screws 140 are provided for connection to the electrical conductors and these screws lie along side the mounting apertures 137. Beneath the screws bores 141 are provided. A push button 139 serves to connect the switch contacts in a manner similar to the handle 68 of the first embodiment. In Figure 26 the contact rod or strip 129 on the left side of the figure denotes the electrical connection to one of the fixed contacts 117.

The advantages rising from a standardization of the heights of the width ratios of special types of switches of the structure as described in the foregoing is explained with reference to Figure 29. In this figure the distribution chamber or the meter board 171 is provided with automatic switches 174 and 175 provided with connecting contacts 172 and 173. The narrower switches 174 are for lower current values up to about 15 amps.; along side of these narrower switches are additional automatic switches with housings 175 of double width and which larger switches are for higher current values or can constitute switches of a special type such as a zero cut-out, signal contacts or the like. With standardization of size components as regards housing dimensions as shown it is possible to substitute for each large automatic switch with the broad housing 175 two switches with the smaller housing 174. It is further possible to replace two of the

narrow switches with one larger switch. Thus with a fixed size of meter or distribution board any combination of narrow and wide switch housings may be effected.

In connection with the substitution of two narrower switches for a wide switch 175 the substitution is possible when the narrow switch is less than half the width of the larger switches. In practice the width of the narrower switches must be somewhat less, that is one-half to 1 mm. less than one-half the width of the wide switch housing, since due to inaccuracies of production and assembly it would not be possible to mount eight narrow switches in the same space as four wide switches.

The advantages resulting from the present invention are easily apparent since meter boards and distribution boards can be equipped with a number of automatic switches 174 double the usual number as regards space factors and it is possible to use both types of switches on the same board adjacent one another and further to arbitrarily select any combination of narrow and wide housing switches since with the dimension requirements satisfied in manufacture the distribution boards can be standardized and accommodate any arrangement of switches necessary for the particular electrical network or networks involved.

It is therefore clear that there has been provided an automatic switch in which the mechanical and electrical components are respectively spatially separated in a housing and which switch provides not only for thermic cut-out on overload but also a magnetic cut-out for a sudden overload or short circuit and in which the structural components of the switch are so dimensioned and arranged within the housing that the rectangular cross sectional area occupied by these parts is no larger than the cross sectional area of the base. There is further provided a switch structure in which abutting oppositely disposed U frames house the respective mechanical and electrical components in spaced relation with apertures provided between the abutting portions of the U frames permitting movement of the movable contact carrying bar and the triple levers.

Additionally, I have provided a switch arrangement embodying a knee joint linkage operable in connection with circuit breaking movement to move the movable contact carrying bar and in which the means responsive to thermic cut-out and the means responsive to magnetic cut-out both include elements cooperating with the same element of the knee joint linkage but in a different manner.

Having described my invention what I claim is:

1. An automatic switch including a rectangular base, means defining a contact chamber thereabove, at least one fixed contact in said chamber, a movable contact normally biased to open position and cooperable therewith, mechanical switching mechanism operably connected with said movable contact for moving the same to and holding the same in circuit closing position, current overload release means cooperable with said mechanism to permit reverse movement of said contact to circuit breaking position and superposing housings respectively receiving and separating the said mechanism from the contacts, and said housings comprising oppositely arranged upper and lower U-frames including bight portions abutting one another.

2. An automatic switch including a rectangular base, means defining a contact chamber thereabove, fixed contact means in said chamber, movable contact means cooperable therewith and normally biased to circuit opening position and including means constituting a contact carrying bar, mechanical switch mechanism operably connected with said bar for moving the same and the contact means associated therewith and holding the same in circuit closing position, current overload release means cooperable with said mechanism to permit reverse movement of said bar to circuit breaking position, superposed housings respectively receiving and separating as the said mechanism from the contact means and the overload release means which latter two means constitute switch components subjected to electrical stress, said mechanism and said components occupying equal cross sectional areas, said mechanism including a switch lever connected to said bar and means biasing the lever and thereby the bar to circuit breaking position, a three part knee joint linkage including a first link, a handle connected thereto, an intermediate link, and a third link operably connected with said switch lever whereby swinging movement of said handle moves said linkage to thereby move said switch lever and the contact bar carried thereby to circuit closing position and said overload release means constituting in part a magnetic coil in the circuit, an armature associated therewith and a hammer lever embodied with said armature and operable when the armature is attracted by the coil due to sudden current overload to displace said linkage to permit said biasing means to move said contact bar to circuit breaking position.

3. An automatic switch as defined in and by claim 2 in which the intermediate link is pivotally connected with the third link and a lug adjacent to the pivot connection is disposed in the path of movement of the hammer lever embodied with the armature and engaged thereby when the armature is attracted by the coil.

4. An automatic switch including a rectangular base, means defining a contact chamber thereabove, a fixed contact means in said chamber, movable contact means cooperable therewith, means constituting a contact carrying bar for said movable contact means, mechanical switch mechanism operably connected with said bar including biasing means normally urging the bar to circuit breaking position and activating means for moving the bar to circuit closing position, current overload release means cooperating with said mechanism to release the same permitting reverse movement of said bar to circuit breaking position, superposed housings receiving and separating the said mechanism from the contact means and the overload release means, said housings comprising oppositely arranged upper and lower U-shaped frames including bight portions abutting one another and parallel front and rear leg means, said overload release means including a magnetic coil, an armature pivotally mounted on the outer face of one of the leg means of the lower frame, said coil abutting the opposite face of said leg means, said leg means having a recess therein into which the armature may move, a hammer lever rigid with the armature and movable therewith, and the upper U-frame receiving the said mechanism having an opening through which the hammer lever extends for cooperation with said switch mechanism.
5. An automatic switch as defined in and by

claim 4 in which the armature is provided with lateral extensions projecting beyond the margins of the recess in the leg means on which the armature is mounted for abutting said leg means to limit the movement of the armature towards the coil.

6. An automatic switch as defined in and by claim 4 and casing surrounding and encompassing both said housings, lug means extending outwardly of the said leg means supporting the armature, a pivot means for the armature supported by said lug means and said lug means extending outwardly of the leg means toward and terminating closely adjacent the casing.

7. An automatic switch as defined in and by claim 4 including a frame carrying said coil, said frame abutting the face of the said leg means supporting the armature and including projecting strips laterally abutting said leg means.

8. An automatic switch as defined in and by claim 1 in which each of the U-frames includes parallel leg means, screw means connecting one leg means of the lower U-frame to the base, the said base having a slot therethrough subjacent the opposite leg means of the lower U-frame and said opposite leg means having a hook on the bottom thereof cooperable with the base after passage through the slot and lateral displacement with respect thereto.

9. An automatic switch as defined in and by claim 8 in which the base projects beyond the narrow sides of the housing and the projecting portions each having a screw receiving aperture therethrough and a contact strip adjacent to said aperture.

10. An automatic switch as defined in and by claim 1 in which the U-frames include opposite leg means, open ended subhousing constituting said contact chamber between the lower leg means and a thin insulating partition closing said chamber and abutting one of the leg means of the lower U-frame.

11. An automatic switch as defined in and by claim 10 in which the means defining the open ended housing includes a longitudinal wall parallel with the major axis of the base and transverse walls parallel with the minor axis of the base, the current overload release means including a magnetic coil in the circuit controlled by the contacts and an armature associated therewith, said coil abutting said longitudinal wall and the said longitudinal wall having ends projecting beyond the transverse walls and the said transverse walls having air passages therein.

12. An automatic switch as defined in and by claim 2 in which the means constituting the contact carrying bar comprises spaced cheeks, a strip connected therebetween, a compression spring connected to said strip and the movable contact means constitutes a contact bridge carried by said spring, said contact chamber having an opening in the upper portion thereof, insulating plates carried on the outer surface on each of said cheeks and said cheeks and plates passing through said opening and being guided by the marginal edges thereof.

13. An automatic switch as defined in and by claim 1 in which the current overload release means includes a bimetallic element and a magnetic coil both in the circuit controlled by said contact means, said switch mechanism including a locking pawl, one end of said bimetallic element being free and adapted to abut said pawl when the said element flexes due to current overload.

said base having a recess therein, a current conducting strip in said base and extending into said recess and means directly connecting the opposite ends of said bimetallic element to said strip.

5 14. An automatic switch including a base, means defining a contact chamber thereabove, fixed contact means in said chamber, movable contact means cooperable therewith and normally biased to open position, mechanical switch mechanism operably connected with said movable contact means for moving the same to and holding the same in a circuit closing position, current overload release means cooperating with said mechanism to permit reverse movement of said movable contact means to circuit breaking position, superposed housings respectively receiving and separating the said mechanism from the contact means and the overload release means, said latter two means constituting components subjected to electrical stress, said base being rectangular in plan and the mechanism and components occupying substantially equal cross sectional areas, the housing receiving the said component comprising three chambers, the first defining said contact chamber, said overload release means including a magnetic coil, the second chamber receiving said coil and an armature associated with said coil and a bimetallic element 10 constituting part of said overload release means in said third chamber.

15 15. An automatic switch as defined in and by claim 14 in which the contact means are mounted in the contact chamber, a ferro-magnetic sheet 20 in said chamber and axially spaced from said contact means, an insulating partition separating the same from said contact means, and said sheet 25 extending perpendicular to the axis of said coil in said second chamber so that said sheet constitutes a magnetic counterpole for said coil.

30 16. An automatic switch as defined in and by claim 14 in which spaced contacts constituting the fixed contact means are disposed in said contact chamber, the movable contact means 35 comprises a movable contact bridge, spaced ferromagnetic sheets extending parallel with the major axis of said bridge and disposed in said contact chamber in spaced relation from said contacts, an insulating partition between said sheets and said contacts and an insulating strip 40 extending perpendicular to said partition between and separating said sheets.

17. An automatic switch as defined in and by claim 14 and a sleeve for said coil constituting an integral part of said contact chamber.

45 18. An automatic switch including a base, means defining a contact chamber thereabove, at least one fixed contact in said chamber, a movable contact normally biased to open position and cooperable therewith, mechanical switching mechanism operably connected with said movable contact for moving the same to and holding the same in circuit closing position, automatic overload release means including an electro-magnetic coil for opening the circuit in case of a sudden heavy overload, as well as a thermostatic member for opening the circuit in case of a prolonged lesser overload, said electro-magnetic coil and thermostatic member cooperable with said switching mechanism to permit reverse movement of said movable contact to circuit breaking position, and superposed housings respectively receiving and separating the said switching mechanism from the switch elements comprising the contacts, the electro-magnetic coil and the 50 55 60 65 70 75

13

thermostatic member which are subjected to electrical stress.

19. An automatic switch as defined in and by claim 18, in which the said base is rectangular in plan and the mechanical switching mechanism and the switch elements subjected to electrical stress occupy equal cross sectional areas.

20. An automatic switch as defined in and by claim 19, for low current loads having the same length factor but at the most half the width factor of switches for higher current loads.

WILHELM LEYHAUSEN.
